UNITED STATES PATENT OFFICE.

JOHN A. ROSE, OF EVERETT, WASHINGTON.

MAST OR POLE SUPPORT.

Application filed February 23, 1926. Serial No. 89,883.

This invention relates to improvements in staff or pole supports and more particularly to devices of that character designed for the mounting of poles to which radio aerials, 5 or the like, may be attached.

The principal object of the present invention is to provide devices for mounting aerial masts, flag poles, and the like, on the roofs of houses, especially at the ridges of roofs 10 and which are adjustable so as to conform to roofs of various slope as well as to flat or angular roofs.

Other objects of the invention reside in the details of construction of the staff holding 15 member and in the attachment of its mounting and brace member as is hereinafter described.

In accomplishing these and other objects of the invention, I have provided the im- 20 proved details of construction, the preferred forms of which are illustrated in the accompanying drawings, wherein—

Figure 1 is a perspective view of a mast mounting device embodied by the present 25 invention.

Figure 2 is a central, vertical section of the same as mounted on the ridge of a roof.

Figure 3 is a horizontal section on line 3—3 in Figure 2.

30 Referring more in detail to the drawings—

The device comprises a tubular sleeve 1 formed from a piece of sheet metal having its longitudinal edges overlapped and secured together to form a tube of desired 35 diameter by means of a bolt 2 extended through slots 3 in the overlapped edges of the piece and secured by a nut 4.

Extending outwardly and downwardly 40 from diametrical opposite points at the lower end of the tube 1 are two supporting legs 5 and 6 which are pivotally mounted on a horizontal pin 7 which serves also as a hinge pin whereby two oppositely directed base plates 8 and 9 are pivotally connected. The 45 plates are mounted on the pin between the legs 5 and 6 of the tube and are adapted to lie against a roof at opposite sides of the ridge, as shown in Figure 2, and for the purpose of attachment, are provided with 50 holes 10 through which screws or nails 11 may be extended.

The opposite ends of the hinge pin 7 extend somewhat beyond the legs 5 and 6 and fixed on the ends thereof are the lower 55 ends of a pair of brace bars 12 and 13 which, at their upper ends, are secured to

the opposite sides of the tube 1 near its upper end, one base being held by a bolt 14 and the other by the bolt 2 which secures 60 the edges of the tube together.

Formed in the opposite side walls of the tube corresponding to the direction in which the base plates 8 and 9 extend, are vertical slots 15 and 16 and pivotally secured by bolts 17 extended between paired, upstanding ears 18 at the outer ends of the base plates, are brace bars 19 and 20 which, at their upper ends, are pivotally fixed by bolts 21 to plates 22 and 23, respectively, 65 that slidably engage with the outer walls of the tube and are secured adjustably thereto by bolts 24 and 25 which extend outwardly through the wall slots 15 and 16 and are held therein by heads 26 at their inner ends.

In mounting the device on the ridge of 70 a roof, it is placed with the hinge pin 7 parallel with the ridge and the base plates lying flatly against the roof at opposite sides of the ridge where they are secured by nails, screws, or other suitable means 11. The tube 75 is adjusted to the desired position and then held by tightening the nuts on bolts 24 and 25 to retain the adjustment. The mast or pole is then inserted in the tube.

The adjustable connections provided between the tube and upper ends of the brace rods permit the device to be applied to roofs of various pitch and also permits one plate to be adjusted for a different pitch than the other. To permit a still further 80 adjustment, I have provided holes 29 in spaced relation adjacent the lower ends of the brace bars 19 and 20 for receiving the attaching bolts 17.

Such devices may be made in various sizes 85 and it is apparent that changes in various details could be made without departing from the spirit of the invention and for this reason I do not wish to be limited only to the device as illustrated.

Having thus described my invention, what I claim as new therein and desire to secure by Letters-Patent, is:

1. A device of the character described, comprising a pair of base plates, a hinge pin pivotally connecting said plates and extending at its ends beyond the latter, a sleeve provided at its lower end with laterally diverging supporting legs that are pivotally mounted on the hinge pin at opposite sides 105 of the base members, and a pair of brace bars pivotally fixed to outer ends of the 110

base plates and adjustably fixed to opposite sides of the sleeve.

2. A device of the character described, comprising a pair of base plates, a hinge pin pivotally connecting said plates and extending at its ends beyond the latter, a mast receiving sleeve having supporting legs at its lower end pivotally mounted on said pin closely adjacent opposite sides of the base members, a pair of brace bars having ends pivotally mounted on the ends of the

hinge pin and their other end fixed to the upper end portion of the sleeve and other brace bars pivotally fixed to the outer ends of the base plates and having connections 15 with the sleeve that are longitudinally adjustable along the latter.

Signed at Everett, Snohomish County, Washington, this 16th day of December, 1925.

JOHN A. ROSE.
